(57) **CLAIM**

The ornamental design for a sex toy as shown and described.

DESCRIPTION

FIG. 1 is a front, left and bottom perspective view of a sex toy, showing my new design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front view of a pair of the sex toy.

The dashed broken lines depict portions of the sex toy that form no part of the claimed design.

The sex toy for the left hand is a mirror image of the sex toy for the right hand as shown in FIGS. 1 to 8, which is also claimed.
